HARRY E. CAMPBELL, OF BALTIMORE, MARYLAND, ASSIGNOR TO CAMPBELL METAL WINDOW CORPORATION, OF BALTIMORE, MARYLAND.

CASEMENT WINDOW.

Application filed December 9, 1924. Serial No. 754,853.

This invention relates to a casement window, and particularly to a form of casement window that can be economically constructed, easily washed, and will be relatively water and weather-proof.

In the accompanying drawings which show an illustrative example of a window embodying my invention, Fig. 1 is a perspective view of an upper and lower corner 10 of the window at the hinge side; Fig. 2 is a sectional view of the lower corner shown in Fig. 1 taken from the outside of the window; Fig. 3 is a sectional view taken at right angles to the view shown in Fig. 2; 15 Fig. 4 is a sectional view through the two side members or jambs of the window with the sash in fully closed position; Fig. 5 is a view similar to Fig. 4 with the sash shown in the position ready to be swung open; 20 Fig. 6 is a view of the hinge side of the window similar to the view shown in Fig. 4 with the sash open; Fig. 7 is a view similar to Fig. 6 with the sash shown in the position to which it is moved for washing; 25 Fig. 8 is a detailed elevation of the locking mechanism with the parts shown in full lines in position in which they appear in Fig. 5 and in dotted lines in the position in which they appear in Fig. 4; Fig. 9 is a detailed 30 sectional plan view of the lower hinge corner of the window and also shows a form of sash adjuster which can be used with my window; Fig. 10 is a side elevation of the locking mechanism of the sash adjuster shown in Fig. 9; Fig. 11 is a sectional view 35 of a portion of the sill showing a form of locking mechanism that may be used with my window; Fig. 12 is a sectional plan view of the parts shown in Fig. 11; Fig. 13 is 40 a sectional view through the side of the window away from the hinge, showing an alternative form of locking mechanism that may be used, and Fig. 14 is a section on line 14—14 of Fig. 13. It may also be noted 45 that Fig. 13 is a section on line 14—14 of Fig. 14.

The window-frame proper is made up of four S-shaped members, of which the jamb members 2 and 3 are substantially identical, 50 and the lintel and sill members 4 and 5 are likewise similar. These four members are welded together at the corners, and because

of the fact that each of these members has three bends, the resulting frame will be very stiff. In practice I have found that 55 a very satisfactory frame can be made if these members are bent from 12-gauge sheet metal. The window sash is primarily made up of four members, all of the same shape in cross section. The members at the sides 60 are designated by the numerals 6 and 7. The member at the top of the sash is numbered 8, while 9 is the member at the bottom of the sash. These four members are welded together, forming an opening to receive the 65 glass 10. In the drawings, the glass 10 is shown as held in place by putty 11, but any other well-known means may be used for this purpose. Attached to the inner faces of the sill and lintel members 4 and 5 are 70 two similar racks 12 which run all the way over to the hinge or pivot side of the window which is the right hand side of the window shown in the illustrative example. Two pinion gears 13 are provided to cooperate 75 with these racks, and pockets 14 are formed at the corners to permit the pinions 13 to move over to the position shown in Fig. 4. A shaft 15 has the two pinions 13 fixed upon it so that these pinions must revolve in 80 unison. In other words, if one pinion 13 moves along its rack 12, the other pinion will move a like distance in the same direction. Stirrups 16 are provided to hold the pinions 13 in engagement with racks 12. 85 Shaft 15 is attached to side member 6 of the sash by two plates 17 in which the shaft is free to rotate. It is thus apparent that if the parts are in the position shown in Fig. 5 the sash can pivot about shaft 15 90 which will act as a hinge for the window. It may be noted, however, that as the axis of this hinge is nearer the center of the window than the extreme right hand edge of the sash, a portion of the sash will swing 95 in towards the room, whereas, the balance will swing outward. Inasmuch as the top and bottom members 8 and 9 which are part of the sash frame, extend respectively up and down so that they overlap members 4 100 and 5, it is necessary to cut away portions of these members to permit the hinged edge of the sash to swing inward (see Fig. 6). Members exactly similar in size and shape to

the portions cut away are permanently attached to members 4 and 5 so that when the sash is closed, these members will fill up the spaces left by the cutaway portions. These members are designated by the numerals 18 and 19 (see Figs. 1 and 3).

In Fig. 4, the window is shown in closed position. It is to be noted here that a portion of member 6 overlaps the outer face of member 2; and therefore while the sash is in this position the window cannot be opened. Accordingly, I supply an operating handle 20 which as an incident to the unlocking of the window moves the sash from the position shown in Fig. 4 to the position shown in Fig. 5. This same handle likewise serves to reverse the movement of the sash when the window is closed.

The operating handle is attached to a plate 21 carried by side member 7, and it is pivoted so that the handle can be raised into the vertical position or lowered to the horizontal position, but movement below the horizontal position is prevented by lug 22 which preferably is formed integrally with plate 21. A keeper arm 23 is permanently fixed at right angles to handle 20 and is beveled at its free end as shown at 24. As shown in Fig. 4, a portion of side member 3 is cut away to receive keeper 23, and within the side member 3 is attached a casting 25. This casting 25 has a flange 26 adapted to cooperate with the beveled portion 24 of keeper 23 to draw the sash toward the room, and to hold the sash in such closed position. It also has a back portion 27 against which the outer edge of keeper 23 will press, so that when the handle 20 is raised, a camming action will be exerted to force the sash into the closed position shown in Fig. 4. In order to provide for the lateral movement of the sash into the opening position, casting 25 carries an arm 26' on which is formed a pin 27'. When handle 20 is pushed down into horizontal position, pin 27' will act as a fulcrum, so that the sash will be moved into the position shown in Fig. 5.

It is to be noted that the racks 12 are longer than is necessary to provide for the above-described lateral movement of the sash. This is to permit the window to be easily washed. As soon as the sash has been swung open to the point where side member 7 is clear of frame member 3, side member 6 can be pushed over away from frame member 2 until shafts 15 come to the end of stirrups 16. This movement may be of sufficient extent to provide an opening of 5 inches, for example, between side member 6 and jamb member 2. This is a large enough space to permit one to reach through and wash the outside of glass 10. The sash is shown in this position in Fig. 7.

With this form of device I prefer to use a form of sash adjuster which will operate to

move the sash into the position shown in Fig. 5, as it is swung to, even if it is in the position shown in Fig. 7 when the closing operation is started. Various forms of sash adjusters may be used for this purpose, the essential feature being that the adjuster shall be such that as the sash is swung in, a positive thrust shall be exerted tending to throw the hinged edge of the sash over laterally to the position shown in Fig. 5, but that provision be made for slippage in the adjuster to permit the sash to move laterally from the position shown in Fig. 5 to the closed position shown in Fig. 4. An illustrative example of one form of sash adjuster adapted for this purpose is shown in Figs. 9 and 10. Here the adjuster comprises two arms 28 and 29, one of which is pivoted to sill member 5 and the other of which is pivoted to the bottom sash member 9. The member 28 carries a ratchet casting 30 and member 29 carries a similar casting 31. A screw 32 passes through these castings and carries a thumb nut 33. Ratchet casting 31 may, if desired, be permanently attached to member 29, but ratchet casting 30 is so arranged that it can slide on member 28 without turning. In order to limit this sliding movement, member 28 has a slot 34 through which screw 32 passes. Members 28 and 29 may be made of such size that when screw 32 is in the position shown in Fig. 9 relative to member 28, the members 28 and 29 will have the same effective length. When this is the case, the points of attachment to the sill and sash should be such that they are approximately one above the other when the sash is in the position shown in Fig. 2. The window can be held open to any desired extent by adjusting the angular relationship of members 28 and 29. When the window is to be closed, thumb nut 30 is loosened so as to permit the two ratchet castings 30 and 31 to rotate relatively to each other. Then as the sash is pulled toward the frame, screw 32 will take the position in slot 34 shown in Fig. 9 where it is in contact with the inner end of this slot. As the window is pulled shut, this contact will insure the hinged edge of the sash being in the proper position. Then as handle 20 is raised into the vertical position and the sash is moved laterally into its final closed position, screw 32 will move through slot 34 towards the free end of member 28 and not interfere with the lateral movement of the sash.

When the window is closed, it may be noted from Fig. 1 that shaft 15 is tightly jammed between members 2 and 6. This provides an air seal along the hinge side of the sash. At the opposite side of the sash, member 7 is drawn in against member 3 because of the beveled shape of the end of keeper 23. In order to arrange for a tight fit of the sash against the frame at the top

and bottom, I provide an adjustable lintel member 35 and a corresponding adjustable sill member 36. These members are attached to frame members 8 and 9 respectively by the use of screws which pass through slotted holes. The contact of the flanges of members 8 and 9 against the outer faces of members 4 and 5 can likewise be adjusted by adjusting the position of the stirrups 16. 10 With a window made in accordance with the foregoing description, it is possible that one not familiar with the operation of the device might move the handle 20 down until the keeper 23 was clear of frame member 3, 15 but without exerting sufficient pressure to move the sash laterally into its opening position. If the sash was then swung out, the leverage exerted might cause severe damage. In order to prevent the window from being 20 opened until it has been moved into the position shown in Fig. 5, I may attach to member 7, preferably below handle 20, a plate 37 provided with a hole 38 (see Figs. 13 and 14). A pin 39 is fixed at a corresponding position in member 3 so that when 25 the sash is moved laterally from the position of Fig. 5 (which is also the position of Fig. 13) into the position of Fig. 4, pin 39 will enter hole 38 and keep the window shut until 30 the reverse lateral movement has taken place.

In Figs. 11 and 12 I show an alternative form of locking device for the free edge of the sash, which will be particularly useful with tall windows. In this form the free edge is drawn against the frame by the lateral movement of the sash independent of the like action of the keeper 23. It may be used either to supplement the action of the keeper, or the keeper may be made to move 40 freely in its casting so that it serves only to force the sash back and forth laterally.

As shown in these figures, I attach to sill member 5, near the free edge of the sash, a casting 40 which is attached to member 5 by screws which pass through slotted openings 41. Extending up from the base of casting 40 are two lugs 42 and 43 which are adapted to cooperate with a plate 44 attached to the underside of the horizontal portion of member 9. As the window is 50 swung closed, plate 44 will be guided by the curved outer faces of lugs 42 and 43 into the gap between these two lugs; then as the sash is moved laterally plate 44 will strike the rear face of lug 43 and owing to the fact that this face is inclined, the sash will be drawn in against the window-frame. It may be noted that lug 42 is made of sufficient depth so as to limit the lateral movement of plate 44 toward the opening position. This will serve to prevent the sash from being moved too far over which might cause the edge of the sash to rub against jamb member 3 as the sash is swung open.

65 It is to be understood that a similar cast-

ing and plate may be attached at the upper part of the window as well as to the lower part as described.

What I claim is:

1. In a casement window, a frame, a sash movable laterally in the frame, but of sufficient size to close the opening in the frame, and pivot mechanism connecting one side of the sash and the frame adapted to permit the sash both to turn relatively to the frame and to move laterally relative thereto. 75

2. A device as characterized in claim 1, in which the pivot mechanism is adapted to permit the pivoted edge of the sash to move in the frame a substantially greater distance, 80 when the sash is swung open, than the sash can move laterally when within the frame.

3. A device as characterized in claim 1, in which the pivot mechanism is adapted to maintain the lateral movement of the top 85 and bottom of the sash substantially equal.

4. A device as characterized in claim 1, in which the pivot mechanism comprises two racks fixed to the frame, a shaft pivotally connected to the sash, two pinions fixed on 90 said shaft adapted to cooperate with said racks and means for holding said pinions in engagement with said racks.

5. In a casement window, a frame, a sash adapted to close the opening in the frame 95 and movable laterally in the frame, pivot mechanism connecting one side of the sash with the frame, a locking handle attached to the other side of the sash, and means attached to the frame adapted to cooperate 100 with said handle whereby when said sash is swung closed and said handle is turned in one direction, the sash will be held against pivoting movement relatively to the frame and will be moved laterally in the frame in 105 one direction, and when the handle is turned in a reverse direction, the sash will be moved laterally in the opposite direction and will be left free to rotate relatively to the frame. 110

6. A device as characterized in claim 5, comprising mechanism in addition to said handle and said means attached to the frame, which mechanism is adapted to hold the side of said sash to which said handle is attached against substantial movement away from said frame until said last-mentioned lateral movement is substantially completed. 115

7. A device as characterized in claim 5, comprising two members carried by said sash and said frame respectively adapted to cause the side of said sash to which said handle is attached to be forced against the frame during such first-mentioned lateral movement of the sash and adapted to hold 120 said side of the sash against substantial movement away from the frame until said last-mentioned lateral movement is substantially completed. 125

8. In a casement window, a frame and a 130

sash adapted to close the opening in the frame and adapted to move laterally a limited distance in the frame, pivot mechanism connecting one edge of the sash and the frame, adapted to permit said edge of the sash, when the sash is swung open, to move laterally in the frame a relatively great dis-

tance, and a sash adjuster connecting the sash and the frame, adapted, as the window is swung closed, to move the pivoted portion ¹⁰ of the sash into the zone of lateral movement of the sash when closed and adapted to permit such lateral movement to take place.

HARRY E. CAMPBELL.
